JOHN WOMELDORFF, OF WARSAW, INDIANA.

Letters Patent No. 86,618, dated February 2, 1869.

IMPROVEMENT IN COMBINED WHEELBARROW FANNING-MILL.

The Schedule referred to in these Letters Patent and making part of the same.

To all whom it may concern:

Be it known that I, JOHN WOMELDORFF, of Warsaw, in the county of Kosciusko, and State of Indiana, have invented a new and improved Wheelbarrow Fanning-Mill; and I do hereby declare the following to be a full, clear, and exact description thereof, reference being had to the accompanying drawings, which are made a part of this specification.

The fanning-apparatus and the shaking shoe may be of any usual or approved construction, with changeable riddles and screens to suit various kinds and conditions of grain or seed to be cleaned; but my invention particularly consists in so constructing the machine that, when the fan, shoe, and upper part of the frame are removed, the lower part will constitute a convenient and efficient wheelbarrow for separate use, and, when the whole is together, the wheel or wheels of the barrow afford means for conveying it from place to place.

In the drawings—

Figure 1 represents a vertical longitudinal section of the complete machine, and

Figure 2, a perspective view of the wheelbarrow detached.

The fan A, hopper B, gearing G, tail-board T, and the shoe C, with grain-boards D, changeable riddles E, and screen F may be of common form, and do not need specific description.

To secure the parts in proper relative position for use as a fanning-mill, and at the same time to adapt them for ready separation, the front part of the upper frame is supported on horizontal lugs or ears H H, fig. 2, and held laterally between shoulders I I.

The rear end of the mill is held against horizontal displacement in any direction by tenons K, projecting downward beneath the fan-cylinder into mortises L L in the lower or wheelbarrow-frame.

The floor M of the wheelbarrow constitutes the bottom of the screening-box when the fanning-mill is in use, and a door, N, is formed in one of the sides, for the purpose of removing the screenings.

The barrow is so constructed that either one or two

wheels, O, may be used, and common handles P P are employed for use in wheeling the barrow, either with or without the upper part of the mill.

To separate the mill, its rear end is lifted straight up until the tenons are clear of their mortises, and it can then be taken off.

By my invention, I am enabled to provide the farmer with two useful and necessary implements for the cost of one. My fanning-mill itself possesses a high degree of efficiency in cleaning any kind of grain or seed, and the great additional advantage of portability, as it may be moved from place to place by hand, even at long distances, without requiring a horse and wagon, as fanning-mills usually do.

When the fanning-mill is not needed, the upper part can be lifted off and set away, when a complete and convenient wheelbarrow is ready for use.

The cylindrical fan-case is connected and strengthened by segmental straps of iron, R, shown in dotted lines in fig. 1, which fit the recesses s in the sides S of the wheelbarrow, to steady and support the upper part.

As an additional means of security, screws or pins may be inserted, through the iron straps R, into holes s' in the barrow-sides, so as to prevent the separation of the parts until said pins are taken out.

Handles are applied at or near the four corners of the upper frame, for convenience in lifting it off.

Having thus described my invention,

What I claim, and desire to secure by Letters Patent, is—

The wheelbarrow fanning-mill herein described, so constructed that the lower portion may be used separately for the ordinary purposes of a wheelbarrow, substantially as set forth.

To the above specification of my wheelbarrow fanning-mill, I have signed my hand, this 2d day of October, A. D. 1868.

JOHN WOMELDORFF.
